ATTORNEY

UNITED STATES PATENT OFFICE

ROBERT M. MAXWELL, OF KANSAS CITY, MISSOURI

AWNNG BRACKET

Application filed January 20, 1930. Serial No. 421,950.

My invention relates to window shades, awnings, and the like, and more particularly to brackets for supporting awnings in openings such as the frame of an automobile window, the principal objects of the invention being to facilitate mounting an awning bracket in a window frame, to clamp brackets securely to side casing members of different character grooved to receive panes and including a casing having a relatively thin groove wall, to reinforce the brackets, and to assure movement of the awning to and from open position in a path parallel with the side edges of the frame.

In accomplishing these and other objects of the invention, I have provided improved details of structure, the preferred forms of which are illustrated in the accompanying drawings, wherein:

Fig. 1 is a perspective view of an awning including a bracket constructed in accordance with my invention mounted in a window frame.

Fig. 2 is a vertical section of the awning in open position showing the face of one side of the frame fragmentarily in elevation, dotted lines indicating the awning in partly retracted position.

Fig. 3 is a section on the line 3—3, Fig. 2, illustrating the means for clamping a bracket plate to one side of the casing.

Fig. 4 is a section on the line 4—4, Fig. 2.

Fig. 5 is a perspective view of disassembled bracket members, a casing plate and bail being shown fragmentarily.

Fig. 6 is a section of the opposite side of the casing from that shown in Figs. 2 and 3, illustrating the means for clamping a bracket plate thereto.

Referring in detail to the drawings:

1 designates a window frame including side casing portions 2 having longitudinal grooves 3 lined with a felt or like element including strip portions 4 and 5 spaced to receive a glass pane.

My invention pertains to brackets including casing plates 6 adapted to be inserted in casing grooves between the felt strips 4 and the flanges 7 of the casings forming the inner walls of the grooves. The plates are secured

to the casings by clamping members particularly adapted for their purpose as presently described.

The groove wall 7 of the casing at the left side of the frame in Fig. 1, is relatively thin, and a special fastening device illustrated in Fig. 3 and including a clamp 8 is provided therefor. The casing at the other side of the frame may have a relatively thick groove wall, including, for example, a raised edge or moulding step 9 as illustrated in Fig. 6, and a different form of fastener including a clamp 10 is provided therefor.

The brackets are modified to suit the different forms of casing sides and clamps to provide a combined assembly that may be easily applied to a frame for securely supporting an awning, in each instance an apertured ear at the lower end of a bracket plate receiving an anchoring bolt 11 that threadedly engages the suitable clamp for moving the clamp into latching engagement with the casing, as presently described.

In the case of the bracket for the right side of the frame in Fig. 1, an ear 12 is provided on the casing plate 6, the ear being bent to engage the end edge of the groove wall 7 and outbent to provide an apertured end portion 13 extending parallel to the plane of the plate and in an offset position therefrom to receive the bolt.

The clamp 10 includes a body portion formed arcuately to snugly fit over and engage the arcuate moulding 9 and an end flange having a screwthreaded aperture to receive the bolt.

The bracket plate 6 for the opposite casing has an ear 14 projecting inwardly of the frame beyond the exterior face 15 of the wall 7 and is provided with an elongated opening or slot 16. An outbent finger 17 on the end of the ear extends laterally toward the window opening and is provided with an opening 18 to receive a latching lug 19 on the end of a washer-like bearing plate 20 having an elongated slot 21. One of the bolts 11 extends through the slots 21 and 16 to receive the clamp 8, and is slidable and freely movable in the slots. The head of the bolt bears against the washer which is anchored by the

lug 19 against rotation when the bolt is rotated to operate the clamp.

The clamp 8 comprises a block or small plate having a threaded aperture 22 to receive the end of the bolt, and a guide arm 23 slidable over the upper edge of the ear 14 in engagement therewith to restrain the clamp against rotative movement when the bolt is rotated to draw the clamp toward the ear.

10 Attention is called to the position of the clamp block 8 substantially at right angles to the plate 6, and to the elongated character of the slots 16 and 21, whereby the bolt-engaged block may move back and forth 15 toward and away from the plate, and the bolt may tilt in the washer and ear 14.

The clamp is moved to the outer end of the bolt for mounting the bracket plate on the casing, and rotation of the bolt will draw 20 the edge 24 of the clamp along the outer face of the wall 7, and into pinching engagement therewith, the slots and clamp being formed to effect clamping engagement of the clamp with the casing wall before the clamp reaches 25 the ear 14.

An arm 25 projecting inwardly from the frame at the upper end of the plate 6 is provided with an opening 26 to receive the spindle on the end of a web roller.

30 My invention further includes a bracket-like arm 27 on each plate 6 spaced from the clamping ear and extending in the same direction as the flange, the arm comprising a relatively broad plate-like member having a 35 portion 28 formed to provide a vertical barrel to receive a hinge pin 29 for swingingly supporting a bail as presently disclosed. The arm is preferably depressed longitudinally, and slit on transverse parallel lines spaced 40 from its upper and lower ends, and the portion between the slits is pressed outwardly arcuately to form the barrel.

45 Swingingly mounted on the arm 27 is a bail support including a disk 30 provided with an edge flange 31 extending from one face thereof partly around its perimeter, and having substantially parallel flattened end portions 32 and 33 adapted to engage the upper and lower edges of the arm 28. The 50 ends 32 and 33 have openings 34 to receive the pin 29 for effecting a swivel joint connection between the disk and the arm.

55 A notched latching disk 35 having less diameter than the disk 30 is concentrically mounted thereon and fixed thereto by a rivet 36. A disk cover or cap 37 has a peripheral flange or rim 38 rotatively slidable on the disk 30 outside of the disk 35, and a rivet-like pin 39 extending through axial apertures in the disks 30 and 35 and cap retains the cap in movable engagement with the disk 30, for guiding and retaining the end of a bail arm adapted to be latched to the disk 35 as presently described.

60 The end of each awning bail has a slot 40

for slidably mounting the bail on the pin 39, said end extending through a slot 41 in the cap rim 38, and a lug 42 adjacent the slot is movable through a rim notch 43 into and out of notches 44, 45 and 46 in the periphery of 70 the disk 35, for latching the bail. The cap thus rotates on the disk 30 when the bail pivots on the pin 39 for lowering or raising the web of the awning.

75 Vertically aligned grooves 47 in the depressed portion of the arm 27 form seats for the hinge pin, and reduce the extent to which the semi-cylindrical portion 28 need be pressed out to receive the pin, and whereby the barrel is recessed in the arm within the 80 plane of the flange 48.

The outer end 49 of the arm is thus located to serve as a stop for the swinging bail support.

85 Bracket or casing plates 6 for the two sides of the casing are similar except for the different character of ears at the lower ends of the plates for cooperating with the clamps adapted for the particular positions.

90 The device as illustrated is adapted to support an awning including a web 50, a roller 51 and bails 52 having inbent fingers 53 engaging the outer edge of the web. The awning is adapted to be extended outwardly from an automobile window, and retracted to a 95 position entirely within the automobile.

95 The brackets are fixed to the inner edge portions of the casing to cause the roller-supporting arms to extend inwardly from the casing, and to permit the glass to be raised 100 to close the window opening. The web of the awning preferably is sufficiently wide to pass close to the side casings of the window when moved outwardly or inwardly, and it is desirable that the bail-receiving edge of 105 the web be substantially parallel with the roller when in extended position, and that the bails move in exact parallelism for extending or retracting the awning.

110 Should the inner faces of the plate-receiving walls 7 of opposite side casings extend otherwise than in the same plane, the plates 6 when mounted in the casings would not lie in the same plane, but would extend at different angles. For example, one of the wall faces might be inclined laterally from parallelism with the plane of the window glass and window, whereby the inner edge of the plate would be tilted away from the glass (Fig. 3) and thus tend to cause the related 115 bail to diverge from the opposite bail.

120 Should the wall face incline oppositely, one bail would incline toward the other bail, and thus destroy desired parallel relation, and cause the awning web to wrinkle.

125 The proper mounting of the roller on the arms 25 would also be hampered if the plates 6 did not extend in the same plane.

130 My improved swivel mounting of the bail-supporting members 30 on the bracket arms

overcomes the disadvantages above referred to, since the members 30 or either of them may be swung laterally on the hinge pin to compensate for any lack of parallelism between the bracket plates and the plane of the window.

The means for effecting lateral swinging of a bail end is distinct from the pivot mounting of the bail end, thus avoiding any interference with the bail latch to affect its effectiveness.

Attention is called to the fact that the web may be moved outwardly to inclined positions as shown in Fig. 2 to serve as an awning, and may be moved further to extend substantially vertically and close the window opening.

What I claim and desire to secure by Letters Patent is:

1. In an awning bracket, a plate adapted for insertion in a window casing groove and having spaced ears extending angularly therefrom adjacent its lower end, a bail-supporting member pivotally mounted on one of said ears, and means including a clamp and a bolt threaded in the clamp and anchored by the other ear for securing the plate to the casing.

2. In an awning bracket, a plate adapted for insertion in a side casing groove to engage the inner face of one wall of the groove, an ear having an elongated slot and projecting from the plate at the lower end thereof and adapted to extend beyond said wall, a bolt mounted in the slot and movable bodily transversely therein, and a clamping block on the outer end of the bolt movable upon rotation of the bolt bodily toward the plate for engaging the outer face of the wall to secure the plate to the casing.

3. In a device of the character described including a bracket, a bail, and means for pivoting the bail to the bracket for vertical swinging movement, laterally swinging means connecting said pivoting means with the bracket.

4. In a device of the character described including a bracket plate and a bail, a disk for pivotally supporting the bail, an ear on the bracket plate, and means hingedly connecting the disk and the ear for effecting lateral swinging movement of the bail.

5. In a device of the character described, a bracket plate having an ear provided with a vertical hinge barrel, a bail-supporting member having a flange provided with aligned openings adapted to register with the channel of the barrel, a hinge pin in the openings and barrel, a bail, and means including a pin in said member for pivotally supporting the bail.

6. In an awning bracket, a plate adapted to be inserted in the groove of a window casing and having an edge flange engageable with the outer face of one wall of the groove,

means including an ear extending from the plate in the direction of the flange and a clamp supported by the ear for clamping the plate to said wall, and means including a second ear projecting from the plate above the first-named ear and a pin mounted in said second ear for supporting a bail of the awning.

7. In an awning bracket, a plate insertable in a casing groove, means for clamping the plate to the casing, an ear projecting from the plate having a depressed portion and a portion outpressed from the depressed portion to form a hinge pin barrel, and bail-supporting means including a member having pin-receiving openings and a hinge pin extending in said openings and through the barrel.

8. In an awning bracket, a casing plate, means for clamping the plate to the casing of a window, an ear on the plate having parallel transverse slits, the portion between the slits being outpressed to form a pin retainer, portions adjacent the slits being depressed to form pin seats, and bail-supporting means including a member provided with pin-receiving openings and a pin extending through the openings and retained between the seats and the retainer portion.

9. In combination with a vertical casing member, a bail, and a laterally swinging bracket for mounting said bail on the casing member.

10. In combination with a vertical bracket plate, a bail, means for supporting the bail, and laterally swinging means for connecting the bail supporting means to the bracket.

11. In an awning bracket, a plate including a body portion insertable in a window casing groove and a flange extending right angularly to said body portion at the outer edge thereof to engage the face of the casing, an ear extending from the outer edge of said flange in alignment therewith and provided with a transverse slot, a bolt movable in said slot transversely of the ear, and means threadedly engaged with the bolt for clamping the plate to the casing.

12. In a device of the character described, a plate, an ear provided with a transversely elongated slot extending substantially at right angles from one edge of said plate, a headed bolt movable transversely of the ear in the slot, a washer mounted on the bolt between the ear and the head of the bolt, and a clamping block threadedly mounted on the bolt on the opposite side of the ear from said washer.

13. In a device of the character described, a plate, an ear provided with a transversely elongated slot extending substantially at right angles from one edge of said plate, a headed bolt movable transversely of the ear in the slot, a washer mounted on the bolt between the ear and the head of the bolt, a

clamping block threadedly mounted on the bolt on the opposite side of the ear from said washer, and means engaging the washer with said ear to prevent rotation of the washer.

14. In an awning bracket, a plate engageable in a window casing groove and having a flange extending laterally substantially at a right angle from the outer vertical edge of the plate to engage the outer face of the casing, and having a vertical edge parallel with the vertical edge of the plate, and vertically spaced ears extending from said vertical edge of the flange, and provided respectively with bail-supporting means and with means for clamping the plate to the casing.

In testimony whereof I affix my signature.

ROBERT M. MAXWELL.
